FIG 1

Inventor

FIG 2 3 G.C.BRADFORD.

By George C. Bradford

Attorney

UNITED STATES PATENT OFFICE.

GRANVILLE C. BRADFORD, OF WASHINGTON, DISTRICT OF COLUMBIA, ASSIGNOR TO GRANVILLE MANUFACTURING CO., OF WASHINGTON, DISTRICT OF COLUMBIA, A CORPORATION OF DELAWARE.

DESIGN FOR A TOILET-POWDER CONTAINER.

47,909.

Specification for Design.

Patented Oct. 5, 1915.

Application filed July 13, 1915. Serial No. 39,688. Term of patent 7 years.

To all whom it may concern:

Be it known that I, GRANVILLE C. BRADFORD, a citizen of the United States, residing at Washington, District of Columbia, have invented a new, original, and ornamental Design for a Toilet-Powder Container, of which the following is a specification, reference being had to the accompanying drawing, forming part thereof.

Fig. 2 is a top plan view of a toilet powder container showing my new design.

I claim:—

The ornamental design for a toilet powder container, as shown.

GRANVILLE C. BRADFORD.

Witnesses:

S. C. HILL,

H. F. MOONEY.
